ELECTRIC SWITCH FOR DOORJAMBS

Hugh W. Batcheller, Newton, Mass., assignor to
Standard Mfg. Co., Worcester, Mass., a corpora-
tion of Massachusetts

Application December 23, 1940, Serial No. 371,230

3 Claims. (Cl. 200—159)

This invention relates to an electric switch of the kind ordinarily mounted in door jambs, such a switch including a spring-pressed plunger which projects therefrom, the switch being mounted in the door jamb in such a way that the plunger is pressed inward by the edge of the door when the door is closed and is allowed to project outward when the door is opened. The switch elements are so arranged with respect to the plunger that the switch is open when the plunger is pressed in and closed when the plunger is allowed to project outward.

It is an object of the present invention to provide a switch of the type described in which the parts are arranged in a novel way so as to simplify the structure and provide for reliable operation as well as economy in manufacture. The switch hereinafter described is characterized by an improved connecting device by which a connection can easily be made with the circuit wire, the spring which presses the plunger being also employed to maintain a firm contact with the wire connector.

For a more complete understanding of the invention, reference may be had to the following description thereof, and to the drawing of which

Figure 1 is a rear elevational view of a switch embodying the invention, showing a circuit wire connected thereto.

Figure 2 is a section on the line 2—2 of Figure 1.

Figure 3 is a section on the line 3—3 of Figure 2, the plunger being shown in a different position of operation.

Figure 4 is a perspective view of a contact member in the switch.

Figure 5 is a fragmentary perspective view of the rear end portion of the barrel.

Figure 6 is a perspective view of the circuit wire connector.

Figure 7 is a perspective view of a fixed contact member in the switch.

As indicated in Figure 2, the switch may comprise an escutcheon plate 10 of suitable size and contour having a central aperture 12 through which projects a plunger 14. A grommet 16 is secured against the rear face of the plate 10 in registry with the aperture 12, this grommet being held in fixed position by any suitable means. Preferably the edges of the aperture 12 are turned in to overlap the inner edges of the grommet as at 18 so as to hold the grommet securely in position. The curled inner edge 18 of the plate 10 also provides a smooth rounded surface to guide the plunger 14. Against the rear

face of the grommet 16 is a fixed contact member 20 which, as shown in Figure 7, consists of a ring or annulus of metal having one or more contact points 22 projecting inward and bent rearwardly out of the plane of the annulus. In the embodiment of the invention shown on the drawing, three such contact points 22 are on the annulus 20. The working members of the switch are housed in a barrel 24 of suitable insulating material. The forward end of the barrel is open and is provided with an outward flange 26 around which is curled a rearwardly extending flange 28 of the grommet 16. The forward end edge of the barrel rests against the annulus 20 and thus holds it firmly in fixed position. The rear end of the barrel 24 is closed as at 30, this rear wall and adjacent side wall being notched as indicated at 32 in Figure 5. The notches 32 are of sufficient depth to form apertures in the side wall of the barrel to permit the entry of a connector 34 secured to the end of a circuit wire 36, the connector comprising a flat plate or strip of copper having a central hole 38 for a purpose to be described.

Within the barrel 24 is a compression spring 40 of bronze wire or other suitable resilient material which is electrically conducting. This wire spring electrically connects a movable contact member 42 and a movable terminal element 44 within the barrel 24. The contact member 42 may conveniently be in the form of an annulus having a flange which fits loosely within the barrel 24, this annulus being secured to the plunger 14. As shown, the plunger 14 is of plastic material which has been molded into the opening of the annulus so that the contact member and plunger are virtually a unitary member. The forward end portion of the spring 40 is received in the space between the side of the plunger 14 and the skirt or flange of the member 42. The spring presses the member 42 against the contact points 22 of the fixed member 20 except when the plunger 14 is pushed inward by a greater force than that of the spring.

At the other end of the spring 40 is the movable terminal element 44 which, as shown, may be in the form of a metal cup slidably fitted within the barrel 24. This cup preferably has a central boss 46 projecting rearwardly so as to bear against the rear wall 30 of the barrel. The sides of this boss are sloping, so that when the connector plate 34 is thrust into one of the notches 32 of the barrel, its leading end rides on the sloping side face of the boss 46, pushing the terminal member 44 sufficiently forward to permit the

connector 34 to slide into the position indicated in Figures 1 and 2. The boss 46 thereupon is pressed into the hole 38 in the connector 34, thus holding the connector yieldably in place. While the connector is in place, the spring 40 presses the terminal member 44 firmly against the connector 34, thus maintaining a good electrical connection. At the same time the spring presses the movable contact member 42 in the opposite direction against the contact points 22 unless the plunger 14 is pushed inward by a door edge or otherwise. In the embodiment of the invention shown, the plate 10 is to be grounded so that the current passes through the spring 40 when the switch is closed by contact of the member 42 with the contact points 22.

It is evident that various changes and modifications may be made in the embodiments of the invention herein shown and described without departing from the spirit or scope thereof as defined in the following claims.

What I claim is:

1. An electric switch comprising a barrel of insulating material open at one end, a ring secured against the open end of the barrel, said ring having a central aperture and a plurality of spaced, rearwardly bent contact points around the aperture, a plunger extending into the barrel through said aperture, a cup-shaped contact member carried by said plunger and adapted to bear against the contact points of said ring, a cup-shaped terminal element seated in the closed end of said barrel and adapted to bear against a connector, and a compression spring having its

ends seated respectively in said contact member and said terminal member.

2. An electric switch comprising a barrel of insulating material open at one end and having an outer flange at the open end, a ring bearing against said open end of the barrel and provided with a series of inwardly and rearwardly projecting contact elements, a grommet overlying said ring and secured to said flange to hold the ring in place, an escutcheon plate overlying said grommet, said ring, grommet and plate having apertures aligned with the axis of said barrel, the inner edges of the plate around its aperture being curled around the inner edges of said grommet to secure the plate to the grommet, a plunger extending into said barrel through said apertures, and switch means within said barrel operable by movement of said plunger.

3. An electric switch comprising a barrel of insulating material having an end wall at one end only and lateral apertures adjacent to said end wall for the insertion of a connector, a terminal element within said barrel movable against said end wall, a second terminal element fixed to the other end of said barrel, a compression spring in said barrel adapted to press said elements in opposite directions and to connect them electrically, and a plunger projecting from within said barrel through said end of the barrel and movable inward against the pressure of said spring to move the adjacent end of the spring away from said fixed terminal element.

HUGH W. BATCHELLER.
